DESIGN FOR A COMBINED CONTAINER AND BRUSH

Theodore Sundin, New York, N. Y., assignor to Metalfield Incorporated, Long Island City,
N. Y., a corporation of New York

Application February 1, 1936, Serial No. 60,948

Term of patent 14 years

To all whom it may concern:

Be it known that I, Theodore Sundin, a citizen of the United States of America and resident of Bronx, New York city, in the county of Bronx, State of New York, have invented a new, original, and ornamental Design for a Combined Container and Brush, of which the following is a specification, reference being had to the accompanying drawing, forming part thereof.

In the drawing:

The figure is a perspective view of a combined container and brush embodying my design.

The sides of the brush not shown are substantially like the corresponding sides shown in the drawing.

I claim:

The ornamental design for a combined container and brush, substantially as shown and described.

THEODORE SUNDIN.
